UNITED STATES PATENT OFFICE

LUTHER R. McINTYRE, OF OSTERVILLE, MASSACHUSETTS

COOKING-UTENSIL LIFTER

Application filed June 19, 1929. Serial No. 372,148.

This invention relates to cooking utensil lifters and an object of the invention is to provide for lifting lids, pans or utensils having handles without the necessity of using 5 cloths to protect the hands.

Further objects of the invention are to provide, in a manner as hereinafter set forth, a device of the character referred to, which is strong, compact and durable, thoroughly reliable for its intended purpose, 10 very convenient and simple in its method of assembly, thoroughly reliable for its intended purpose and comparatively inexpensive to manufacture.

15 With the foregoing and other objects in view, the invention consists in the novel construction, combination and arrangement of parts as will be hereinafter more specifically described and illustrated in the accompanying drawings, wherein is disclosed 20 an embodiment of the invention, but it is to be understood that changes, variations, and modifications may be resorted to, without departing from the spirit of the claim 25 hereunto appended.

In the drawings, wherein like reference characters denote like parts throughout the several views:

Figure 1 is a top plan view of the lifter 30 in accordance with the present invention.

Figure 2 is a vertical transverse detailed section taken substantially on the line 2—2 of Figure 1, and

Figure 3 is a transverse detailed section 35 taken substantially on the line 3—3 of Figure 1.

Referring to the drawings in detail, 4 and 5 designate a pair of elongated rods disposed longitudinally and of polygonal cross 40 section. The rods are preferably formed of metal, but it is within the contemplation of the invention to form the same of any suitable strong material, capable of suspending the weight to which the device may be 45 adapted. Normally the rods 4 and 5 are disposed in the same plane and in spaced relation to each other. Adjacent the outer end and at a point adjacent the middle of the rod, they are rockably connected together as indicated generally at 6, and 7,

which connections will be described in detail hereinafter.

It is to be understood that the rods 4 and 5 are disposed in spaced parallelism and the rockable connections will be set forth in 55 detail.

Referring to Figure 3 of the drawings, one of the rockable connections 6 or 7 are shown in the enlarged form, and it is believed that a description of one will clearly 60 present an understanding of the other. A pair of U-shaped staples 8, 9, have the legs thereof extending through the body portions 4 and 5 and the ends of the legs are bent over and clinched as at 10, 11, in the outer 65 faces of the rods. The plane of the staple 9 is disposed at right angles to the plane of the staple 8 and the bight portion 11 of the staple 9 extends through the bight portion 12 of the staple 8, thereby forming a 70 rockable connection between the two rods. Both bight portions 11, 12, project inwardly from the respective inner faces 13, 14, of the rods, so that ample space will be provided for rocking said rods. 75

Adjacent the outer rockable connection 6, there is secured to one of the rods 5, an angular shaped hook, indicated generally at 15, having one leg 16 thereof disposed outwardly from the upper face of the rod 5. 80 The other leg 17 of the hook is in abutment with and secured to the upper face of the rod 5, by suitable hold fast devices, (not shown).

A substantially U-shaped frame indicated 85 generally at 18 is suspended from the outer end of the rod 4, and a second or other U-shaped frame indicated generally at 19 is suspended from the other rod 5.

Both of the frames 18, 19 are formed of 90 metal rods of bendable nature, but rigid enough when bent to the desired form to support pans, lids or other cooking utensils, used in the home. Both of the frames 18, 19, are substantially U-shaped in configuration, 95 and are disposed with their bight portions 20, 21, extending longitudinally of the bars 4, 5. The forward legs 22 of the frame 18, decline forwardly and laterally from its upper end and the rear leg 23 declines rear- 100

wardly and laterally from its upper end, both of which merge at their lower ends with the bight portion 20 which is curved laterally with respect to the legs. At points 5 24, 25, where the legs 22, 23, merge with the bight portion, the body of the frame 18 is curved inwardly as will be clearly understood by reference to the drawings. The upper ends of the legs extend through the 10 body portion of the rod 4, as indicated at 26 and the ends thereof are flattened out as indicated at 27, whereby the frame 18 is rigidly riveted to the rod 4.

The forward leg 28 of the frame 19 declines forwardly and laterally and the rear leg 29 declines rearwardly and laterally from their upper ends and are formed with inwardly curved portions 30, 31, where they merge with the bight portion 21. The bight portion 21 curves laterally from the lower 15 ends of the legs 28, 29.

The upper ends of the legs 28, 29, extend through the body of the rod 5, as indicated at 32, and the upper ends are flattened out 25 as at 33, to rigidly rivet the frame 19 to the handle 5. It is pointed out that the respective frames 18, 19 are riveted to the handles 4, 5, adjacent the points of hinged connections 6, 7, so as to give proper balance 30 to objects held between the frames.

In the application of the device, in accordance with this invention, the outwardly inclined leg 16 may be used for lifting any type of lid from a cooking utensil, prior to 35 the lifting operation with the frames 18, 19. In the drawings, the dotted lines 34 indicate a pie plate, a pan, or other cooking utensil held by the present device, resting upon the opposed bight portions 20, 21 of the frame.

40 Various sizes of cooking utensils may be lifted by the present device, inasmuch as by 105 rocking the handles 4, and 5 with respect to each other, the distance between the respective plate portions of the frame may be 45 altered as desired.

It is to be understood that by describing in detail, herein, any particular form, structure or arrangement, it is not intended to limit the invention beyond the terms of the 50 claim or the requirements of the prior art.

55 What is claimed is:

A cooking utensil lifter of the class described comprising a pair of elongated rods of the same length longitudinally disposed and rockably connected at points spacedly disposed from one another, a substantially U-shaped frame depending from each rod and having the ends of the legs anchored to each one of the rods adjacent the points of 60 rockable connection, the bight portions of said frame being curved laterally from the legs, said frames having the legs thereof declining laterally and the curved bight portion of each extending laterally in an obtuse angle with respect to said legs, and an angu- 65

lar shaped hook secured to one of the rods adjacent the outer end thereof.

In testimony whereof I affix my signature.

LUTHER R. McINTYRE.
